OIL PUMP

Filed May 6, 1926

Inventor
Harry T. Woolson

By *John Harness* Attorney

UNITED STATES PATENT OFFICE

HARRY T. WOOLSON, OF DETROIT, MICHIGAN, ASSIGNOR TO CHRYSLER CORPORATION, OF HIGHLAND PARK, MICHIGAN, A CORPORATION OF DELAWARE

OIL PUMP

Application filed May 6, 1926. Serial No. 107,040.

It is the primary object of my invention to construct a cheap and economical oil pump for use in an automobile to pump oil and simultaneously draw air from a vacuum tank during certain points of the cycle of rotation of the pump.

Another object of my invention is to pump oil and draw air into a chamber, keeping the air entry segregated from the oil inlet and outlet of the chamber.

A further object of my invention is to create enough air suction in an oil pump having a short oil conduit from the oil source to satisfactorily operate a vacuum tank.

With the above and other objects in view, my invention consists in the arrangement, combination and construction of the various parts of my improved device as described in the specification, claimed in my claims and shown in the accompanying drawing, in which:

Fig. 1 is a side elevation of my improved device shown partly in section.

Fig. 2 is a plan view of my improved device shown partly in section.

Fig. 3 is a sectional view of my improved device taken on line 3—3 of Fig. 1.

I have shown a housing 10 having a flanged bottom edge 11 to which is secured by bolts 12 a cover plate 13 forming with the housing 10 a chamber 14. Extending up from and integral with the top 15 of the housing 10 is a tubular casing 16 having the aperture 17 therein terminating at one end into the chamber 14 and at the other end into a reduced aperture 18 formed by a shoulder 19 on the top of the casing 16.

Placed in an eccentric position for rotation in the chamber 14 is a head 20 of a pump member, said head having a portion of its circumference touching as at point 21 the inner wall of the housing 10. A shaft 22 projects up from the center of the head 20 into the aperture 17 and integral with the shaft 22 is a stem 23 positioned in the aperture 18. A spiral groove 24 is cut into the shaft 22 to permit oil to lubricate the same during rotation.

A slot 25 divides the head 20 into two equal parts and positioned for reciprocation in the slot are the block members 26 and 27 that have

their outer ends chamfered as at 28. Coiled springs 29 hold the blocks 26 and 27 yielding against the wall of the chamber. Grooves 30 are cut into the top of the head 20 adjacent the chamfered sides 28 of the blocks 26 and 27. 55

An oil intake passage 31 having an opening 32 in the chamber 14 and an oil outlet passage 33 having an opening 34 into the chamber 14 are integral parts of the housing 10. A drain plug 35 is placed in the end of the passage 31 and also threaded into this passage intermediate its ends is a pipe 36 adapted to convey oil from a conventional source of oil supply such as the crank case of an automobile. 60 The outlet passage 33 may be suitably connected to the various points in an internal combustion engine where oil is used. 65

Formed in the cover plate 13 is a conduit 37 with the opening 38 leading therefrom into the chamber 14 and positioned between the 70 openings 32 and 34. Connected with this conduit 37 is an intake line 39 adapted to draw air from a conventional type vacuum tank, not shown.

In the practical operation of my improved device the head 20 is rotated clockwise in the chamber 14 by the shaft 22, stem 23 and a source of rotative power, not shown, connected with a flange 40 on the end of the stem 23. The rotation of the head 22 simultaneously draws air and oil into different portions of the chamber 14 that are segregated by the blocks 26 and 27 and the point 21 where the head 20 touches the wall of the housing 10. 75 80 85

The air is drawn from the conventional vacuum tank into the chamber 14 in back of the blocks 26 and 27 after the same have passed the outlet opening 34 and one of the grooves 30 is an open connection with the 90 opening 38 of the conduit 37 in the cover plate 13. At the same time oil is drawn into the chamber in back of the blocks 26 and 27 after they have passed the inlet opening 32. This oil is forced around by the blocks to the outlet opening 34. The point where the head 20 touches the wall of the housing 10 prevents the oil from circulating around the chamber 14 and allows only air to fill the space after the blocks 26 and 27 pass the outlet 34 and 100

until the same pass the inlet 32 at which point oil is admitted. Thus the amount of air drawn into the pump can be determined so that the same is sufficient to set up a suction in the vacuum tank to draw the proper amount of gasoline for consumption in the automobile.

It will be noted that the suction of air created in the pump is not dependent upon the length of the oil intake pipe 36, and that a certain amount of air is drawn into the pump at two periods during a complete cycle of the pump. The entry of the air is entirely independent and segregated from the pumping of oil into and out of the chamber 14.

It will be obvious that various changes may be made in the arrangement, combination and construction of the various parts of my improved device without departing from the spirit of my invention and it is my intention to cover by my claims such changes as may be reasonably included within the scope thereof.

What I claim is:

1. A device of the class described, comprising a housing, a cover plate secured to the bottom of said housing forming a chamber therewith, an inlet and an outlet passage for said chamber integral with said housing, a conduit integral with said cover and having an opening into said chamber, and means adapted to simultaneously draw oil into and out of a portion of said chamber through said passages and intermittently draw air into the remaining part of said chamber through said conduit in the cover.

2. A device of the class described comprising a housing, a cover plate secured to said housing forming a chamber therewith, an inlet and an outlet passage into and from said chamber and integral with said housing, a conduit integral with said cover plate and having a slotted opening into said chamber, a pump member having a slot in the center thereof placed in eccentric position in said chamber, block members having chamfered outer ends positioned for reciprocation in said slot, means positioned between said blocks forcing the chamfered ends to

bear yieldingly against the wall of said housing, a groove in the top of said head adjacent each of said blocks, and means rotating said pump member to simultaneously draw oil into and force it out of a portion of said chamber through said passages and to draw air into the remainder of the chamber through said slotted opening in the cover and the grooves in said pump member.

3. A device of the class described comprising, a housing having a chamber therein, two segregated inlets and a segregated outlet adapted for communication with said chamber, rotating means intermittently drawing air into a portion of said chamber to create

a vacuum and continuously drawing oil into another portion of said chamber.

4. A device of the class described comprising, a housing having a chamber therein, means for progressively increasing the area of a portion of said chamber and progressively decreasing the area of another portion of said chamber, an inlet passage communicating with said increasing portion for a predetermined interval, another inlet passage communicating with said increasing portion after the communication of said first inlet passage and an outlet passage communicating with said decreasing portion.

5. A device of the class described comprising a housing, a cover plate secured to the bottom of said housing forming a cylindrical chamber therewith, spaced inlet and outlet passages in the cylindrical wall of said chamber, an eccentric rotor within said chamber, reciprocating vanes carried by said rotor, the outer ends of which engage the cylindrical wall, a slotted inlet passage in the end of said chamber, and a passage in said rotor adapted to form an intermittent communication between said slotted passage and the space between the cylindrical wall and the rotor.

6. A device of the class described comprising a housing having a chamber therein, two segregated inlets and a segregated outlet adapted for communication with said chamber, an eccentric rotary member within said chamber, reciprocating vanes carried by said housing forming a pair of chambers between the wall of said chamber and said rotary member, and a passage carried by said rotary member adapted to intermittently form a communication between one of said inlet passages and one of said chambers.

7. In an oil pump for an internal combustion engine, the combination of a rotor eccentrically disposed in a pump body, an outlet for said pump, an oil inlet for said pump, an air inlet for said pump, one of said inlets being closed by an end surface of said rotor, and a channel in said rotor connecting said inlet with said pump during a part of the intake cycle of said pump.

8. In an oil pump for an internal combustion engine, the combination of a rotor eccentrically disposed in a pump body, an outlet for said pump, an oil inlet for said pump, an air inlet for said pump adapted to be closed by an end surface of said rotor, and a channel in said rotor connecting said air inlet with said pump during a part of the intake cycle of said pump.

9. In an oil pump for an internal combustion engine, the combination of a rotor eccentrically disposed in a pump body, an outlet for said pump, an oil inlet for said pump, an air inlet terminating in a crescent shaped slot in said pump body and adapted to be covered and uncovered by one of the end

faces of said rotor, and a channel in said rotor connecting said slot with said pump during a part of the intake cycle of said pump.

10. In an oil pump for an internal combustion engine, the combination of a rotor eccentrically disposed in a pump body, an outlet for said pump, an oil inlet terminating in said pump body in the form of an elongated slot, an air inlet adapted to be covered and uncovered by one of the end faces of said rotor, and a channel in said rotor connecting said air intake with said pump during a part of the intake cycle of said pump.

HARRY T. WOOLSON.
